UNITED STATES PATENT OFFICE.

CARL FREDRIK HYLTÉN-CAVALLIUS, OF HALMSTAD, SWEDEN.

GARMENT-SUPPORTER.

No. 902,084.

Specification of Letters Patent.

Patented Oct. 27, 1908.

Application filed April 8, 1908. Serial No. 425,824.

To all whom it may concern:

Be it known that I, CARL FREDRIK HYLTÉN-CAVALLIUS, lieutenant-colonel, citizen of Sweden, residing at Halmstad, Sweden, have 5 invented new and useful Improvements in Garment-Supporters, of which the following is a specification.

The present invention refers to a device for holding up the trousers and consists of 10 hooks fastened at the waistband and a row of strings or laces arranged inside that piece of clothing which is worn immediately above and nearest to the trousers, most frequently the waistcoat. The hooks on the 15 waistband pointing outwards will of their own accord hook into one or the other of the aforesaid strings or laces of the other wearing apparel, and the trousers will thereby be held up without any further trouble. When 20 for instance the strings are arranged on the waistcoat it will in order to pull off the trousers only be necessary to unbutton the waistcoat and the trousers. If the trousers are held up in the ordinary way by means 25 of braces these must, besides the aforesaid unbuttoning of the waistcoat and trousers, also be unbuttoned. The same is the case when the trousers are put on. By the present invention it is therefore only necessary 30 to button the trousers and the waistcoat. This makes the present arrangement much more comfortable than the one hitherto used, and the improvement becomes still more evident for stout persons or when in cold and 35 damp weather the hands and fingers are numb. The fewer buttons then to be buttoned the better.

When the vest is buttoned, the hooks will 40 of their own accord catch into the strings or laces, and these being arranged horizontally will offer elastic holding-points for the trousers. The arrangement does not cause any inconvenience as the piece of wearing apparel outside the trousers needs not sit 45 tighter than usual. The weight of the trousers will be divided between the shoulders, that is to say over a larger surface than is the case with ordinary braces.

The invention is shown on the accompanying drawing, in which

Figure 1 shows a waistcoat provided on the inside with strings, Fig. 2 shows the upper part of a pair of trousers provided with hooks, Figs. 3 to 6 show different views of 50 the hook and how it is fastened, Figs. 7 and

8 show two different ways of arranging the strings.

The waistcoat being as a rule the wearing apparel immediately above the trousers the strings are arranged inside the lower part of 60 the waistcoat as shown in Fig. 1.

The strings *a* which are held together in different places by narrow cross-pieces *b*, are sewn on to the lower part of the waistcoat *c*.

On the outside of the waistband *d* (Fig. 65 2) the outwardly pointing hooks *f* are either sewn on direct or they may be fastened by means of a plate *g* (Fig. 3) on the inside of the waistband and carrying two elastic pins *h* that are forced through the waistband and into two holes of a small part *k* on the outside of the waistband, the said part *k* being provided with the hook (Fig. 3).

The hooks *f* are fastened to the trousers 70 so that they will be adjacent the row of 75 strings *a*, and they will consequently, when the waistcoat *c* is buttoned, project between the strings and hook onto one of these. The strings *a* and cross-pieces *b* may be made in 80 pieces of suitable length. They are sewn on 85 to the waistcoat at the cross-pieces *b* whereby the intermediate pieces of string are quite free. The strings and cross-pieces may also 90 be fastened on by buttons, each cross-piece 95 being buttoned on to a button *m* in the waistcoat (Fig. 7).

Fig. 8 shows a special arrangement of the invention where the strings are fastened to 90 a very light piece of wearing-apparel *n* having the shape of a waistcoat the fabric of 95 which is of a relatively open mesh. The strings have a buckle and strap so that the whole device can lie close to the body. This arrangement is especially adapted for 100 sporting persons who want to dispense with coat and waistcoat in order to move more freely.

In order to make the waistcoat more capable of resistance it may be provided with 105 yokes *p* (Figs. 1 and 8).

I claim:

1. A supporter comprising in combination, a supporting garment having shoulder engaging portions and provided on its interior with a plurality of engageable elements arranged to afford engagement at a plurality of different vertical points, and a supported garment provided with a plurality of supporting members adapted to extend within and automatically engage the elements.

2. A supporter comprising in combination, a supporting garment having shoulder engaging portions and provided on its interior with a plurality of parallel longitudinally disposed, engageable elements arranged to afford engagement at a plurality of different vertical points, and a supported garment provided with a plurality of supporting members adapted to extend within and automatically engage said elements.
3. A supporter comprising in combination, a supporting garment provided on its interior with a plurality of parallel strings, and a supported garment provided with a plurality of supporting members and adapted to extend within said strings and automatically engage the same.
4. A supporter comprising in combination, a supporting garment provided on its interior with a plurality of parallel strings, 20 said garment being provided with yokes or supporting elements extending from said strings to points around the shoulder portions of said garments, and a supported garment provided with a plurality of hooks 25 adapted to extend within said strings and automatically engage the same.

In testimony whereof I have signed my name to this specification in the presence of two subscribing witnesses.

CARL FREDRIK HYLTÉN-CAVALLIUS.
